ATTACHMENT-PLUG FOR ELECTRIC CIRCUITS.

1,080,325.

Specification of Letters Patent.

Patented Dec. 2, 1913.

Application filed February 24, 1913. Serial No. 750,299.

To all whom it may concern:

Be it known that we, FRANK H. CHAPMAN and OWEN E. KENNEY, citizens of the United States, and residents of Toledo, in the county of Lucas and State of Ohio, have invented a certain new and useful Attachment-Plug for Electric Circuits; and we do hereby declare the following to be a full, clear, and exact description of the invention, such as will enable others skilled in the art to which it appertains to make and use the same, reference being had to the accompanying drawings, and to the characters of reference marked thereon, which form a part of this specification.

This invention relates to electrical devices, and particularly to the plug members of the quick connecting type of plug and socket couplings for electric circuits, but is not restricted to such use as it may be used in any connection for which it may be adapted or appropriate.

The object of our invention is to improve upon the construction of the plug members of circuit connecting devices of this character whereby to cheapen the cost of manufacture and to enhance the practicability and commercial value thereof.

The invention is fully described in the following specification, and while, in its broader aspect, it is capable of embodiment in numerous forms, a preferred embodiment thereof is illustrated in the accompanying drawing, in which—

Figure 1 is a side elevation of a plug member embodying our invention. Fig. 2 is a view of the contact end thereof. Fig. 3 is an elevation of a plug member partly inserted in a socket member with parts of each in central longitudinal section. Fig. 4 is a central longitudinal section of the plug member different from the section shown in Fig. 3, and Figs. 5 and 6 are side and inner end views, respectively, of the plunger part of the plug.

Referring to the drawings, A designates the socket member of the coupling, which member is of customary or any suitable construction, and has the central contact part 1 and the spirally-grooved or threaded lining 2 forming the other contact of the socket.

The plug member B of the coupling, in which member the features of our invention reside, comprises the body part 3 and the

plunger part 4, which latter is mounted for axial reciprocatory movements in a longitudinally extending socket 5 in one end of the body part 3. A coiled compression spring 6 is disposed in the base of the socket 5 and acts against the plunger 4 to cause its outer end to be yieldingly projected a short distance without the open end of the socket 5, as shown, such distance being normally limited by a spring catch 7, which is carried by the plunger 4 in a recess 7' at one side thereof and engages in a registering socket or opening 8 in the wall of the socket 5. The catch 7 has a beveled surface to permit its depression by contact with the wall of the socket 5 when the plunger is being inserted into position within such socket and to enable the plunger to have inward depressing movements from its normal position in the socket 5 should the opening 8 not be of sufficient length for the catch to move freely therein during such depressing movement. To remove the plunger from the socket 5 it is only necessary to insert a pin, or the pointed end of some other suitable instrument, into the opening 8 and to bear inward therewith against the catch 7 to depress the same from within the opening 8, the spring 6 then acting to force the plunger outward.

The plunger 4 is preferably, but not necessarily, of cylindrical form in cross-section, and is provided on one side thereof adjacent to its outer end with a raised boss or radially projecting part 9 and has a recess 10 extending from the inner side of such boss to the inner end of the plunger. A conductor-strip 11 is mounted within the base portion of the recess 10, being secured therein, in the present instance, by a screw 12, and has its outer end portion offset and extending over the boss 9 to provide a contact face 13 therefor. The combined depth of the boss 9 and contact part 13 is sufficient to project through a registering notch or opening 14 in the outer end portion of the wall of the socket 5, and preferably a short distance beyond the outer peripheral surface of such wall to insure contact of the part 13 with the lining 2 of the socket member A when the plug member is inserted in said socket member. The working of the boss 9 and contact part 13 through the opening 14 also serves to guide the reciprocatory move-

ments of the plunger in the plug body 3 and to insure the proper assembling of the plug parts.

One of the lead-in wires 15, 16, which enter the base portion of the socket 5 through an opening 17 in the outer end of the body part 3 of the plug member, extends into the recess 10 of the plunger over the contact strip 11 and is clamped to the latter by a binding screw 18. The other lead-in wire is projected, in the present instance, through a longitudinal passage 19 in the plunger and has its free end engaged to a contact screw or part 20 which is disposed centrally of the outer end of the plunger in position to have contact with the contact part 1 of the socket member A when the plug member is inserted therein, as shown in Fig. 3.

If desired the outer end portion of the body part 3 of the plug member may have a ferrule 21 of metal or other suitable material fitted therearound to provide a smooth wearing surface for contact with the lining of the socket member A. This ferrule is not intended, however, to form any part of the electric circuit as the electrical contact between the plug member and the lining 2 of the socket is through the contact part 13 with which one of the lead-in wires 15, 16 is connected. The ferrule 21 has openings or notches therein in register with the notch 14 and opening 20 of the body part 3 of the plug member.

The means employed, in the present instance, for securing the members A and B of the coupling together, when inserted one within the other, comprises a ball or locking part 22, which is mounted in an opening in the wall of the plug socket 5 and is adapted to have its inner end project within the socket 5 and to work in a registering longitudinal groove or channel 23 in the plunger 5 when the outer side of the ball or part 22 is substantially flush with the outer periphery of the socket wall. When the plug member is forced into the socket member and the contact end of the plunger 4 has contact with the part 1 of the socket member, said plunger is depressed within the socket 5 of the plug and a raised surface 24 at the outer end of the groove 23 moves into contact with the ball or part 22 and forces it outward into engagement with a registering spiral groove in the lining 2 of the socket member. The imparting of a slight turning movement in clockwise direction to the plug member B after the part 22 has been projected into thread engaging position causes a tightening together of the coupling members. The raised surface 24 is preferably composed of metal or other hard surface to prevent a wearing of said surface when the part 22 is in thrust contact therewith. It is evident with this form of

coupling that the two contact parts 11 and 20 of the plug member are carried by the plunger 4 of such member for movements therewith, and that the closing of the circuit through the coupling members is not dependent upon the making of contact with the socket lining 2 by a part carried by the body 3 of the plug or by the retaining parts which serve to couple the two members of the coupling together. It is preferable in the assembling of the plug members to dispose the coupling means 22-24 at the opposite side of the plug to the contact part 11 so that the outward forcing of the coupling part 22 into engagement with the socket lining 2 will effect a forced contact of the part 11 with such lining.

We wish it understood that our invention is not limited to any specific construction or arrangement of the parts except in so far as such limitations are specified in the claims.

Having thus described our invention, what we claim as new and desire to secure by Letters Patent, is—

1. A coupling for electric circuits comprising a socket member having separate contact parts and a plug member, said plug member having two sections which are relatively movable upon an insertion thereof into the socket member, one of said sections carrying a pair of contact parts for contact with the respective contact parts of the socket member when inserted therein, and means separate from said contact parts and automatically operable by a relative movement of the plug member sections when inserted within the socket member to hold the two members in coupled relation.

2. A coupling for electric circuits comprising a socket member having separate contact parts and a plug member, said plug member having sections which are relatively movable upon an insertion of the plug a predetermined extent into the socket member, contacts carried by the plug member for contact with the respective contact parts of the socket member when the plug is inserted therein, and means separate from said contact parts and automatically operable by a relative movement of the plug sections when inserted into the socket member to hold the two members in coupled relation.

3. In a coupling of the class described, a plug member having a socketed portion and a plunger mounted in said socketed portion, a conductor element having a portion countersunk in the plunger and a portion which is radially offset relative to the plunger to form a contact part for side contact with the wall of a socket member into which the plug may be inserted.

4. In a coupling of the class described, a plug member having a socketed body part

with a recess in the outer end portion of the socket wall, a plunger longitudinally movable in said socket, a contact part fixed to said plunger and projecting through said recess and a separate contact part carried by said plunger.

5. In a coupling of the class described, a plug having a body member provided with an end socket and having an opening in the 10 wall of such socket, a plunger mounted for reciprocatory movements in said socket, means influencing an outward movement of the plunger relative to the socket and spring catch means carried by the plunger for engagement with said opening, to limit the 15 normal outward movements of the plunger relative to the socket and adapted to be depressed from within said opening by the insertion of an instrument into the latter.
- 20 6. In a coupling of the class described, a socket member having base and wall contacts within the socket thereof, a plug member having two telescoping portions mounted for relative axial movements, means

influencing an outward movement of said 25 portions, a contact part fixedly carried by the inner of said portions and working radially therefrom through a part of the other portion to adapt it to have contact with the wall contact of said socket, a second contact part carried by the inner one of said portions for engagement with the base contact part of said socket, and means carried by the plug member and operable by a relative movement of the portions there- 30 of to coöperate with the socket wall to hold the members in coupled relation when the plug member has been inserted a predeter- 35 mined distance into the socket member.

In testimony whereof, we have hereunto 40 signed our names to this specification in the presence of two subscribing witnesses.
